ABSTRACT OF THE DISCLOSURE

An expendable immersion temperature-sensing assembly adapted to be thrown into a bath of molten material to measure the temperature thereof including weight structure and a tube loosely fitted thereon and supporting lead wires and heat softening means releasably securing the weight structure to the tube, the heat softening means having the characteristic of melting as the assembly enters a zone at elevated temperature thereby effecting separation of the weight structure from the tube so as to reduce the buoyancy of the portion of the assembly which enters the bath of molten material.

The present invention relates to an expendable immersion temperature-sensing assembly of the throw-in type and has for an object the provision of an expendable immersion temperature-sensing assembly adapted to be thrown into a bath of molten steel in a basic oxygen furnace to measure the temperature thereof.

The basic oxygen furnace due to its tremendous efficiency enables steel to be produced at a much faster rate than in furnaces of the open hearth type. However, basic oxygen furnaces present a more difficult problem for temperature measurement of the bath than the open hearth type of furnace. Expendable immersion thermocouples were first introduced commercially for the measurement of bath temperatures in open hearth and electric furnaces in 1958. Examples of such expendable immersion thermocouples are disclosed and claimed in Mead Patents 2,999,121 and 3,038,951, Moore Patent 3,024,295, Parker Patent 3,048,642 and Robertson et al. Patent 3,055,961. Such expendable thermocouples normally are introduced into the furnace by a manipulator or handle of rigid construction. When using this type of manipulator to insert an expendable immersion thermocouple into a basic oxygen furnace it is necessary to stop the oxygen blast and tilt or position the furnace so that an operator can immerse the expendable type thermocouple for obtaining a temperature measurement. In view of the fact that the total time for steel production in a basic oxygen furnace runs from about 30 to 45 minutes, this means that a delay of three or four minutes to obtain a temperature reading becomes a very important percentage of the overall production time, and hence, becomes a relatively expensive reading. In view of this, various types of "throw-in" expendable immersion thermocouple assemblies have been developed for obtaining a quick temperature measurement in a basic oxygen furnace, without the necessity of withdrawing the oxygen lance and tilting or repositioning the furnace. Examples of such throw-in assemblies are disclosed in a co-pending application Ser. No. 446,000, filed Apr. 6, 1965 by Louis R. Jones, Jr., now abandoned in favor of continuation application Ser. No. 796,258, filed Dec. 9, 1968, and in Canadian Patent No. 681,508, issued Mar. 3, 1964.

Since the distance to the surface of the bath with the furnace in upright position is in the order of 30 to 40 feet in a basic oxygen furnace, the aforementioned throw-in expendable thermocouple devices utilize relatively long

lengths of leadwire cable, for example, in the order of 50 feet. In the preferred forms of throw-in thermocouples, the coil of lead wire is carried by a support which permits the lead wire to pay out and avoid tangling when the unit is dropped or thrown into the furnace. As disclosed in the aforesaid application, the preferred form of support for the coil of lead wire comprises a cardboard tube on which the lead wire is coiled. The cardboard tube also provides protection for the lead wire near the expendable thermocouple unit as it passes down through the furnace. The lower end of the cardboard tube is provided with a metal weight so as to cause the expendable thermocouple unit to be immersed in the molten metal bath. However, due to the buoyancy of the cardboard tube, a relatively heavy weight is required in order to move the expendable thermocouple unit below the surface of the bath. Accordingly, the present invention provides for automatic separation of the weight and cardboard tube at the time when or before the weight enters the bath, so as to reduce the buoyancy of the assembly.

In accordance with the present invention, there is provided an expendable immersion temperature-sensing assembly adapted to be thrown into a molten bath to measure the temperature thereof such, for example, as a bath of molten steel in a basic oxygen furnace. Such assembly includes weight structure having a density greater than that of the material of the molten bath, the weight structure having a cavity open at the immersion end thereof. A body structure including material having both heat insulating and electrical insulating characteristics is fitted into the open end of the cavity to form a plug therefor. A refractory protected temperature-sensing device is supported by the body structure and projects outwardly therefrom away from the cavity. The end of a cable comprising heat insulated lead wires extends into the weight structure from the opposite end thereof and is electrically connected within the cavity to the temperature-sensing device. A cardboard tube is loosely fitted onto the end of the weight structure into which the lead wires extend. There is further provided heat softening means releasably securing the weight structure to the cardboard tube. The heat softening means has the characteristic of melting as the immersion end of the weight structure enters the furnace which is a zone at elevated temperature thereby effecting separation of the weight structure from the cardboard tube so as to reduce the buoyancy of the assembly that penetrates the bath. The heat softening means, in the preferred form thereof, comprises a plastic tape which holds the cardboard tube to the weight structure for a time; however, it permits separation before or at the time the temperature sensing device hits the bath, separation of the cardboard tube from the weight structure permitting the latter to sink below the surface of the molten bath unaffected by the buoyancy of the cardboard tube. At the same time the cardboard tube provides protection for the lead wire as it enters the furnace and particularly at the point where the cable enters the weight.

For further objects and advantages of the present invention, and for a more detailed description thereof, reference is to be had to the following description taken in conjunction with the accompanying drawing, which is an elevational view, partly in section, of an expendable thermocouple assembly embodying the present invention.

Referring to the drawing there has been illustrated an expendable thermocouple assembly 10 embodying the present invention and particularly suited for measuring the temperature of the molten bath in a basic oxygen furnace. The assembly 10 includes a pair of dissimilar thermocouple elements 11 and 12 connected together at one of their ends to form a hot or measuring junction 13 for the thermocouple. The serially connected thermo-

couple elements 11 and 12 are inserted in a refractory protective tube 14 which may be made of silica, quartz or "Vycor." The opposite ends of the refractory tube 14 are supported within a body structure 16 which may be made from refractory cement, ceramic, wood or other material having both heat insulating and electrical insulating characteristics such, for example, as disclosed in the aforesaid Parker Patent No. 3,048,642 or the other above-mentioned U.S. patents, or in the copending application Ser. No. 193,706, filed May 10, 1962 by Davies, issued Jan. 17, 1967 as U.S. Patent No. 3,298,874. A fusible protective cap 17 encloses the refractory protected thermocouple and is mounted on the body member 16. It will be seen that the expendable thermocouple unit, as thus far described, is similar to such units disclosed in the aforesaid U.S. patents and applications. The thermocouple elements 11 and 12 will normally be made from noble metal material and thus, in order to use short lengths of these elements, their ends opposite the hot junction 13 are connected within the body 16 to short lengths of extension lead wire 19 and 20 which extend from the opposite end of the body member 16 for connection to a measuring circuit.

As may be seen in the drawing the body member 16 is tapered and is adapted to be received in the open end of a cavity 18a within a metal weight structure 18. The end of the weight structure 18 which receives the expendable thermocouple unit is referred to as the immersion end as that is the end which enters the molten bath first. In order to protect the thermocouple assembly during storage, shipment, and when it is dropped into the furnace the immersion end of the weight structure 18 is provided with three projecting feet 18b spaced equidistantly about the thermocouple unit.

The lead wire extensions 19 and 20 are adapted to be connected by crimped connectors 21 and 22 to corresponding lead wires 23 and 24 which are a part of heat insulated lead wire cable 25. As pointed out in the aforementioned Jones application, the cable 25 is long and flexible so that it may be coiled in various shapes and includes an outer casing which is solidly packed with asbestos insulation or equivalent insulation including rubber compositions, and a heavy paper wrapping sufficient to protect the lead wires 23 and 24 during the time required to record a temperature measurement. In order to keep the lead wires 23 and 24 from contacting each other within the cable 25, such lead wires are provided with individual electrical insulation elements 23a and 24a, respectively, which may be color coded or otherwise marked to identify polarity of the thermocouple. The cable 25 is adapted to extend through a passage 18c of the weight structure 18 at the end opposite the immersion end. The passage 18c is only slightly larger at its inside diameter than the outside diameter of the cable 25. Thus, it will be seen that the cable 25 and the body member 16 effectively plug the opposite ends of the cavity 18a and prevent entry of molten metal into the area surrounding the crimped connectors 21 and 22.

The metal weight 18 is preferably made from steel or cast iron so that the weight structure will have a density greater than that of the molten bath. The upper end of the weight structure 18 (as shown) is provided with a reduced diameter 18d terminating in a shoulder 18e against which the lower end of the cardboard tube 26 abuts. The outside diameter of the portion 18d is slightly less than the inside diameter of the cardboard tube 26 and the depth of the shoulder 18e corresponds approximately to the wall thickness of the cardboard tube 26. The dimensions of these parts are so selected that the cardboard tube will loosely fit onto the weight structure 18. The cardboard tube 26 is adapted to be releasably secured to the weight structure 18 by heat softening means such, for example, as a plastic tape 27. The plastic tape 27 is adapted to overlap the joint between the metal weight 18 and the adjacent end of the card-

board tube 26 and may be applied thereto in sections or it may extend completely around the tube 26. The tape 27 has the characteristic of melting as the weight structure 18 enters the furnace thereby effecting separation of the weight structure from the cardboard tube 26 so as to reduce the buoyancy of the portion of the assembly 10 which enters the bath.

In one embodiment of the invention the weight structure 18 had a weight of about five pounds, two ounces and an outside diameter of about 3½ inches and a diameter at 18d of about 3⅓ inches. The cardboard tube 26 had a wall thickness of about ⅛ inch and an inside diameter of about 3¼ inches. The tape 27 consisted of black, plastic electrical tape ½ inch wide.

While in the preferred form of the invention the heat softening means 27 for releasably securing the weight structure 18 to the cardboard tube 26 is an adhesive plastic tape, it is to be understood that other equivalent heat softening or heat destructible means may be utilized and are intended to be generically included by the language "melting" or the like as used in the claims. For example, the heat softening means may comprise adhesive securing the end of the cardboard tube 26 to the shoulder 18e, such adhesive having a heat softening point substantially below the temperature of the molten metal bath.

Or, for example, the tube itself may have a section of wall near the assembly of lesser cross section and the tube made of a heat-softenable material so that it will quickly melt in the region of lesser cross section and separate the tube from the assembly. Thus, my invention embraces broadly the concept of a support for an extended length of lead wire preferably in coil form, and preferably in a single layer helical coil within a tube, which, by reason of the heat in the vicinity of the molten bath, is during its travel toward the molten bath severed from the weighted assembly, thus to avoid the effect of buoyancy of the tube whether vented or not.

Alternatively, the means for releasably securing the weight structure to the cardboard tube may comprise other materials such as metal and the like which are fusible, combustible, or melt at temperatures substantially below the temperature of the molten bath. Examples of such materials are solder and other equivalent low temperature metals as well as plastic bands and the like. While the tube 26 has been described as being made of cardboard it is to be understood that the tube 26 may be made of other material. The lead wires in the cable 25 may be of compensating materials as well known in the art or they may be ordinary copper lead wires as disclosed in the aforesaid copending application of Jones. The term "coil" as used in the claims is defined generically as including a spiral, helix, hank, accordion fold, wad or any other predetermined arrangement of the supply of heat insulated lead wire cable.

From the foregoing it will be seen that the expendable immersion temperature-sensing assembly 10 includes a weighted subassembly comprising a temperature-sensing device such as an expendable thermocouple unit, and weight structure 18 which imparts to the weighted subassembly a density greater than that of the molten material the temperature of which is to be measured to assure sinking of the subassembly into the molten material. The lead wires 23 and 24 of extended length are adapted to be connected to one end of the temperature-sensing device and are supported by means secured to the weighted subassembly, the last named means being separable from the weighted subassembly in response to the heat in the vicinity of the molten material thereby to separate the same from the weighted subassembly so that the density of the weight structure will sink the temperature-sensing device into the molten material during the temperature measuring period.

It is to be understood that the present invention is not limited to the specific arrangements described and illus-

trated herein but further modifications thereof may be made within the scope of the appended claims.

What is claimed is:

1. An expendable immersion temperature-sensing assembly adapted to be thrown into a bath of molten material to measure the temperature thereof comprising:
5
a weight structure having a density greater than that of the material of the molten bath,
a temperature-sensing device supported in protruding relation at an end of said weight structure,
10 heat-insulated lead wires extending into said weight structure and electrically connected to said temperature-sensing device,
a tube loosely fitted onto said weight structure and supporting said lead wires, and
15 heat softening means releasably securing said weight structure to said tube, said heat softening means having the characteristic of melting as the assembly enters a zone at elevated temperature thereby effecting separation of said weight structure from said tube so as to reduce the buoyancy of the portion of
20 said assembly which enters the bath of molten material.
2. An expendable immersion temperature-sensing assembly according to claim 1 wherein said heat softening means comprises plastic adhesive tape overlapping the joint formed between said tube and said weight structure.
25
3. An expendable immersion temperature-sensing assembly according to claim 1 wherein said heat softening means comprises a ring of material extending around the
30 lower end of said tube and overlapping the joint between said end of said tube and said weight structure.
4. An expendable immersion temperature-sensing assembly according to claim 1 wherein said temperature-sensing device comprises a refractory protected thermo-couple device.
35
5. An expendable immersion temperature-sensing assembly according to claim 1 wherein said tube is a cardboard tube and said heat insulated lead wires are coiled in the form of a helix within said cardboard tube and
40

engage the inside circumference of said tube so as to allow the lead wires to pay out freely and without tangling when said assembly is dropped into the bath of molten material.

6. In an expendable immersion temperature-sensing assembly, a weighted subassembly including a temperature-sensing device and weight structure imparting to said weighted subassembly a density greater than that of the molten material the temperature of which is to be measured to assure sinking of said subassembly in the molten material, and

10 means secured to said weighted sub-assembly for supporting an extended length of lead wire connected at one end to said temperature-sensing device, said last-named means being separable from said weighted subassembly in response to the heat in the vicinity of the molten material thereby to separate the same from said weighted subassembly so that the density of said weight structure will sink said temperature-sensing device into the molten material.

7. The method of supporting an extended length of lead wire connected at one end to a temperature-sensing device during the time interval that device and a weighted structure forming a part of its assembly is traveling from a point in spaced relation to a bath of molten material, which comprises:

15 disposing the extended length of lead wire about a support affixed to said assembly and subsequently applying heat from the vicinity of said molten material to separate the support from said assembly while said assembly is traveling toward said molten material for sinking of the same into the molten material.
